UNITED STATES PATENT OFFICE

JAMES F. CONNOR, OF CLEVELAND, OHIO

BRUSH

Application filed November 9, 1931. Serial No. 573,753.

This invention relates to brushes and particularly to a method of setting bristles firmly in place in a brush back.

The present day requirements necessitate a brush that can be held under a stream of scalding water without loosening the tufts and without allowing the water to seep into the sockets in which the tufts are held. Wooden backed brushes are not suitable for this purpose, as hot water tends to swell the wood and destroy the finish on the back. Accordingly an effort has been made to construct brushes of this character with metallic brushes which appear to be successfully marketed are those wherein the tufts are locked into place by means of a wire, which is looped around the tufts, and is securely anchored to the back of the brush. This is not only unsightly but it leaves many crevices and obstructions in which foreign material may be lodged.

Some of these objections have been overcome by making blind sockets, forcing the tufts into the sockets and then anchoring them in place with a staple. This method of anchoring has been demonstrated to be practical but unless the staple is securely locked, the bristles have a slight tendency to lateral movement, and thus admit foreign material into the sockets where it is inaccessible for removal.

An object of the present invention is to retain the advantage of the stapled tuft in connection with the metallic brush and to provide a method of anchoring the tuft, which will insure a water-tight connection between the tuft and the surface of the metal immediately surrounding the socket. A further object is to provide a brush wherein the bristles, which comprises each tuft, are firmly held in erect, compact position. In this connection, my invention is directed toward a method which can be readily utilized in connection with existing brush stapling equipment, and which will provide a brush back substantially smooth on both sides thereof.

Referring now to the drawing, Fig. 1 is a sectional view through a brush back embodying my invention and illustrating one form of sealing arrangement; Fig. 2 is a similar

view illustrating a modified form of sealing arrangement; Figs. 3, 4 and 5 are different steps in the method that I employ for carrying out my invention.

Referring to Fig. 1, the brush back 10 is shown as having sockets 11 and 12. A tuft 13 occupies the socket 11, while the socket 12 illustrates the form of it prior to the insertion of a tuft. It will be noted that the socket 12 has a boss 14 extending around the marginal edge thereof, and that the socket proper comprises aligned cylindrical passageways 15 and 16, which are connected by chamfered portions 17. The inner portion 16 is adapted to receive the staple 18, which is looped around the tuft, and is driven into the socket simultaneously with the tuft. I have found that the staple receiving portion 16 should be smaller than the portion 15 in order to obtain the best results in anchoring the tuft. Furthermore, I have found that the chamfered portion provides a satisfactory shoulder which may be swaged over the staple to more securely lock it in position. The swaging operation may be accomplished by corners on the needle 20, which is used for inserting the tuft and staple into the socket. To seal the portion 15 against the entrance of water and of foreign material, I flatten the boss 14 after the tuft has been inserted and locked into the socket. Such flattening operation may be accomplished by forcing the conical guide 21 into contact with the boss after the needle shall have been withdrawn from the socket. Thus, as is shown in Fig. 1, the boss is flattened until it lies in the same plane as the bristle side of the brush forcing the walls of the socket 15 against the tuft. In Fig. 2, the boss 14-A is shown, as being flatter than the boss 14. The net result of this difference in formation is that a larger portion of the wall of the socket 15 is forced into contact with the tuft as is illustrated at 22.

In Figs. 3, 4 and 5, I have illustrated the steps in the method of accomplishing my invention. In Fig. 3, the tuft 13 with its associated staple 18 is being forced downwardly through the guide 21 and into the sockets 15, and 16 by means of the needle 20. In Fig. 4,

the staple and tuft have been driven into the socket and the corners 25 of the needle have engaged the chamfered portion 17 of the socket and forced part of it in contact with the top of the staple thereby locking it more effectively into place. In Fig. 5, the needle has been withdrawn and the guide 21 has been forced into contact with the back 10 with sufficient pressure to flatten the boss, and thereby to seal the tuft. Thus, the tuft is tightly compressed on a relatively large surface adjacent the mouth of the socket, and the bristles are held in compact, erect position.

I have found that the brush made in accordance with my invention presents a smooth attractive appearance, that the bristles are firmly locked in place, and that the tuft sockets are completely closed around the tufts. A brush made in accordance with my invention can be made in a very economical manner,

and can be subjected to the action of scalding water without impairing the firmness with which the bristles are held in place. Furthermore, the sockets are completely sealed against entrance of foreign material.

70

I therefore claim:

1. A brush back having a socket opening therein, a tuft folded within the socket, a staple embracing the tuft an intermediate portion of the wall of the socket being swaged over the staple, and the wall of the socket adjacent the outer end thereof being swaged against the tuft in sealing relation therewith.

75

2. A brush having a socket opening from one side thereof, a folded tuft therein, the inner wall of the socket being swaged to lock the tuft in place, and the outer wall of the socket being swaged to provide a moisture-proof seal around the tuft.
